UNITED STATES PATENT OFFICE.

ARCHIBALD M. STRACHAN, OF MINNEAPOLIS, MINNESOTA.

GRAIN-HEADING MACHINE.

Application filed October 16, 1922. Serial No. 594,950.

To all whom it may concern:

Be it known that I, ARCHIBALD M. STRACHAN, a citizen of the United States, residing at Minneapolis, in the county of 5 Hennepin and State of Minnesota, have invented certain new and useful Improvements in Grain-Heading Machines, of which the following is a specification.

My invention relates to grain heading machines. An object is to provide a machine which will cut off the heads of grain and deliver them in an efficient and expeditious manner with the saving of much time and labor as compared with machines now 10 in use with which I am familiar. Another object is to provide a machine of this character which may be economically and readily constructed of standard material and parts. I accomplish the objects of my invention by 15 providing a wheeled frame in combination with means for producing a current of air to deliver the cut-off heads.

The full objects and advantages of my invention will appear in connection with 20 the detailed description, and the novel features embodied in my inventive idea will be particularly pointed out in the claims.

In the accompanying drawings which illustrate an embodiment of my invention in 25 one form,—

Fig. 1 is a side elevational view of the machine. Fig. 2 is a top plan view of a portion of the machine. Fig. 2^A is a vertical 30 cross-sectional view through the receiving box. Fig. 3 is a view in vertical section on the line 3—3 of Fig. 1. Fig. 4 is a view in vertical section on the line 4—4 of Fig. 3. Fig. 5 is a view in vertical section on 35 the line 5—5 of Fig. 3.

Referring to the construction shown in the drawings, the numeral 10 designates a cylindrical casing which may be made of sheet iron and is provided with a longitudinal slot 12 which, as best shown in Fig. 45 5 extends for nearly the lower front quadrant of the casing. One end of the casing is closed by a plate 14, and the other end of the casing is partly closed by a segmental 50 plate 16 which covers the space corresponding to the slot 12 and extends somewhat beyond the upper and lower edges of this slot. Supported centrally by the inner corner of this plate and by the inner end of 55 a radial bar 18 is a journal box 20 which contains a bearing 22 on a shaft 24 extend-

ing centrally and longitudinally through the casing. Secured centrally on the plate 14 is a journal box 26 which contains a bearing 28 on the shaft 24. Secured to the reduced 60 end of the shaft 24 outside the casing is a wheel 30 on the periphery of which is a cam flange 32 which extends between two spaced rollers 34 and 36 mounted on the end of a reciprocating cutter bar 38, the cutters of 65 which are adapted to cut the straw below the heads of grain. Secured to the shaft 24 adjacent the wheel 30 is a large sprocket wheel 40. A sprocket chain 42 runs over this sprocket wheel and over a small sprocket 70

wheel 44 secured to a shaft 46 having bearings 48 and 50 contained in journal boxes 52 and 54 carried on the upper side of the casing 10. Secured to the other end of the shaft 46 from that which carries the sprocket wheel 75 44 is a large pulley 56 over which runs a belt 58 which also runs over a small pulley 60 secured to a shaft 62 to which is secured a fan 64 mounted adjacent the partly open end 80 of the casing 10 so as to force a blast of air through this casing. Secured to the shaft 24 by bolts 66 are a plurality of curved blades 68, the outer edges of which closely engage the inner surface of the cylindrical 85 casing 10. The blades 68 in succession during their rotation form temporary chambers in the casing 10 so that air cannot escape from the casing through the slot 12. Leading from the other end of the casing 90 is a delivery pipe 70. The casing 10 is adjustably mounted on the front of a wheeled frame which as shown may be the frame of a motor vehicle. In order to thus mount the casing it is provided with pairs of ears 72 and 74 and secured to these ears are arms 95 76, the ends of which are secured to a shaft 78 rotatably mounted on the frame. Secured to the shaft 78 is an upwardly extending arm 80 which is connected by a link 82 with a hand lever 84 pivotally attached 100 to the machine within reach of the driver. Upon operating the lever 84 the casing is either raised or lowered. For operating the shaft 46, a pulley 86 is secured thereto and a belt 88 runs over this pulley. This belt 105 passes over idlers 90 and 92, and then around a pulley 94 secured to the power shaft 95 of the vehicle. In order to keep the belt taut, the idler 90 is mounted on a pivoted support 96 to which a spring 98 is 110 attached for holding the idler against the belt. The pipe 70 discharges into a receiv-

ing box 100 mounted on the rear portion of the vehicle frame. This box may be arranged to dump automatically and its bottom is shown provided with an inverted V member 102 in order that an air space may be left under the pile of heads deposited on the ground. Since this automatic dump box is no part of the invention claimed in the present application, it need not be described in detail.

The operation and advantages of my invention will now be obvious. The wheeled frame carrying at its front the casing and cutting mechanism is driven over the ground; the rotary blades 68 sweep the heads of grain backward into the slot 12 so that the straw below the heads is brought into engagement with the cutters. The cut-off heads are swept into the casing where they are subjected to the air blast produced by the fan 64 which carries them through the delivery pipe 70 into the receiving box 100. It will be noticed that the fan is driven from the shaft 46 at an increased rate of speed while the shaft 24 is driven from shaft 46 at a decreased rate of speed.

I claim:

1. A grain heading machine comprising a wheeled frame adapted for movement over the ground, a horizontal cylindrical casing supported by said frame and having a longitudinal slot therein, cutting mechanism at one edge of said slot, a rotatable shaft extending longitudinally through said casing, blades attached to said shaft which closely engage the inside surface of said casing, said blades in succession during their rotation forming temporary chambers in said casing, a fan for producing a blast of air through

said casing, and means for driving said fan at a greater rate of speed than that of said shaft.

2. A grain heading machine comprising a wheeled frame adapted for movement over the ground, a horizontal cylindrical casing supported by said frame and having a longitudinal slot therein, a reciprocating cutter mounted at one edge of said slot, means for operating said cutter, a shaft extending longitudinally through said casing, means for rotating said shaft, blades secured to said shaft which closely engage the inside surface of said casing, said blades in succession during their rotation forming temporary chambers in said casing, and means for producing a blast of air through said casing.

3. A grain heading machine comprising a wheeled frame adapted for movement over the ground, a horizontal cylindrical casing supported by said frame and having a longitudinal slot therein, a reciprocating cutter mounted at the lower edge of said slot, a shaft extending longitudinally through said casing, means for rotating said shaft, blades attached to said shaft which closely engage the inside surface of said casing, a cam wheel secured to said shaft for operating said cutter, said blades in succession during their rotation forming temporary chambers in said casing, a fan at one end of said casing for producing a blast of air through said casing, means for driving said fan, and a delivery pipe extending from near the opposite end of said casing.

In testimony whereof I hereunto affix my signature.

ARCHIBALD M. STRACHAN.
